UNITED STATES PATENT OFFICE.

FREDERIK BASENAU, OF AMSTERDAM, NETHERLANDS.

STEAM TRAP.

Application filed July 18, 1923, Serial No. 652,284, and in Germany July 21, 1922.

This invention relates to steam traps or devices for discharging water of condensation from steam pipes or heating systems and relates more particularly to steam traps in which the water of condensation escapes by a continuously open orifice uncontrolled by a float valve or other organ controlled by some motive power.

I have found by exhaustive experiment that by a proper formation of the orifice it is possible to obtain a maximum efficiency in the discharge of water of condensation coupled with a minimum escape of steam without employing any valve or closing member. The principle on which such an orifice is constructed is that it will offer a progressively increasing resistance to the flow of a mixture of steam and water as the wetness of the mixture increases so that in time as the pressure difference pushing the mixture through the orifice falls, the liquid, water, is not pushed through but settles as a globule of water in the orifice where it performs the function of a valve. The orifice thus, under these conditions, provides a free passage for water but is an effective bar to the passage of steam so long as the pressure difference of the fluid on opposite sides of the nozzle is within the limit of the back pressure set up by the resistance of the nozzle to the passage of water. If now the resistance of the nozzle in such a case is so designed that it is equal to the desired normal or maximum pressure difference it is sought to maintain between the inlet pressure to the steam trap and the outlet or discharge pressure, the nozzle will not only perform the function of an effective steam trap but will also act as an automatic relief valve. The reason of this is that when an excess pressure difference occurs, the globule of water in the nozzle will be blown out and vapour will escape until the pressure difference again becomes less than the back pressure set up by the resistance of the nozzle to the passage of water.

I have found that the best results are obtained by forming the continuously open orifice as a conical nozzle converging in the direction of flow of the fluid through the trap and having the sides formed as part of a cone with an angle of 65° at its apex, that is in section the sides will make an angle of 32.5° with the axis. The size of the free opening at its most constricted point depends upon the probable rate of condensation and must be adequate to drain the conduit or

heating system at full load, but the ratio of the wide to the constricted part of the nozzle is in the neighbourhood of 1/6th as measured by the diameters, that is to say 1/36th as measured by areas.

My invention thus consists of a steam trap having a casing or body part provided with an inlet and a discharge for water of condensation and a continuously open conical nozzle interposed as a resistance in the path of flow of the fluid through the trap so that the nozzle converges in the direction of flow with its sides at an angle of 65° .

The invention also embodies the organization of this nozzle orifice with a valve and a sieve so that the trap may be "blown-off" in such a manner as to remove impurities intercepted by the sieve.

In order that my invention may be more clearly understood several examples embodying the same have been shown in the accompanying drawings. In said drawings,

Fig. 1, is an elevation showing the nozzle,
Fig. 2, is a vertical longitudinal section 80 thereof,

Fig. 3, is a vertical longitudinal section showing a steam trap provided with my improved nozzle,

Fig. 4, is a similar section showing a modification,

Fig. 5, is a horizontal section taken on the line 5—5 of Fig. 4,

Fig. 6, is a sectional elevation showing another modification, and

Fig. 7, is a horizontal section taken on the line 7—7 of Fig. 6.

In the example shown in Figs. 1 and 2 my improved nozzle *a* is in the form of an externally screw-threaded plug having an axial bore or passage comprising a cylindrical portion *b*¹ and an outwardly tapering or conical portion *b* located at the discharge end of the nozzle. The solid angle at the apex of the conical portion is 65° , the angle of the conical wall to the axis being 32.5° which value has been entered in Figs. 1 and 2. The discharge end *c* of the portion *b* is in the form of a sharp annular edge *c'*.

Such a nozzle forms a resistance in the direction of flow of the fluid, the resistance being greatest at the most constricted part. The amount of this resistance for any given nozzle will vary with the nature or specific gravity of the fluid and will be greater for water than for vapour. If now the resist-

ance to water flow is substantially equal or greater than the pressure fall which is required to cause a steam flow through the orifice, water of condensation will pass but steam will be retained owing to the fact that it cannot force the water through the orifice at the generally prevailing pressure differences on each side of the orifice. I find that these conditions are most nearly attained in practice by the form described and shown in the drawings.

In Fig. 3 I have shown my improved nozzle as mounted in a casing d provided with a flange d' for connecting the same to a steam pipe or the like for removing therefrom the condensed water. The casing is divided by a partition wall d^4 into two chambers or passages d^2 and d^3 and the chamber d^2 contains a sieve e separating the main portion from the nozzle a screwed into a bore of the partition wall d^4 . Coaxially of the nozzle a an opening is made in the outer wall of the casing which is normally closed by a screw plug f , and which permits cleaning of the nozzle. The condensed water is discharged through the nozzle a and into the chamber d^3 from whence it passes either into the open or is conducted through a pipe in the usual manner for further use. The chambers d^2 and d^3 are adapted to be connected with each other through a second passage normally closed by a hand operated blow-off valve g , which valve may be temporarily opened for diverting any excessive quantity of condensed water from the nozzle a and for permitting the sieve e to be cleaned. The object of the sieve is to keep foreign matter such as particles of packing material away from the nozzle a , and it is desirable from time to time to remove such foreign matter from the sieve. For this purpose, the valve g may be opened, thereby allowing the steam to flow at high velocity past the bottom face of the sieve and to dislodge any impurities.

The operative part of the steam trap is the nozzle a the construction of which has been described in detail with reference to Figs. 1 and 2. The operation does not depend on any movable parts which would render the action unreliable, particularly where the trap is required to be operative over long periods.

In the modification shown in Figs. 4 and 5 my improved nozzle a is mounted in a valve cone h having an axial bore h^1 in line with the bore of the nozzle and transverse bores h^2 . The valve cone is disposed within a casing i having an inlet i^1 and an outlet i^2 and adapted to be connected by flanges i^3 and i^4 respectively to supply and discharge pipes for condensed water. The valve cone h is normally forced on its seat i^5 by a hand operated valve stem h^3 carrying at its top end a hand wheel h^4 . The valve

cone h is formed with an annular shoulder h^5 and the stem h^3 is provided with a flange h^6 . On the said shoulder and flange a cylindrical sieve j is fitted, so that the condensed water has access to the nozzle a only through the sieve, which thus prevents any impurities from reaching the nozzle a . The sieve may be inspected through a glass plate k fitted in the wall of the casing i at a part opposite to the inlet i^1 and fixed in position by an annular screw k^1 .

As appears more particularly from Fig. 5 the inlet passage i^1 is curved out of radial direction and into a direction tangentially of the sieve j and the wall of the casing surrounding the same, so that when valve h is opened steam admitted through the inlet passage i^1 flows in the direction of the arrow I and circumferentially of the sieve thus removing therefrom any foreign matter deposited thereon. When turning the stem h^3 for unseating the valve, the sieve j secured thereto is gradually turned so that the whole circumference of the sieve is exposed to the action of the jet of steam.

Fig. 5 also shows that the inner or discharge end of the inlet passage is reduced in cross-section and in the form of a nozzle, so that the velocity of the steam striking against the sieve is increased. Thereby the cleaning action is improved.

In the modification shown in Figs. 6 and 7 the nozzle a is mounted within a casing l having an inlet l^1 , a downwardly directed tubular portion l^2 , a tubular portion l^3 having a cap or lid o screwed thereto, and a tubular portion l^5 closed by a glass disk l^6 and an annular cap l^7 . On the tubular portion l^2 a sleeve n is screwed which is connected at its bottom end with a pipe p . The sleeve is externally hexagonal in form to permit a wrench to be applied thereto. As shown the joints are made in a manner similar to pipe joints, and the construction is particularly suitable for low pressure steam.

The sleeve n is formed internally with a flange m foraminated near the wall of the sleeve as shown at m^2 and formed with an upwardly projecting axial tubular portion m^1 having the nozzle a screwed therein. To the top face of the flange a valve ring m^3 is secured which normally bears on a valve seat ring m^4 secured to the bottom face of the tubular portion l^2 . The tubular portion m^1 is formed with a reduced portion m^5 , and the lid o is formed with a downwardly projecting stud o^1 . On the said reduced portion m^5 and the stud o^1 a cylindrical sieve q is fitted which is in sliding engagement with the stud o^1 and secured to the reduced portion m^5 by a pin q^1 . A coiled spring o^2 tends to force the sieve downwardly. The inlet passage l^1 is curved laterally in the manner described with reference to Figs. 4 and 5.

The normal operation of the trap will be understood without explanation. For cleaning the sieve q the sleeve n is screwed downwardly by means of a wrench. Thereby the valve m^3, m^4 is opened and steam rushes through the inlet t^1 , against the sieve, and through the valve. In this case the sieve is gradually turned with the sleeve n whilst being subjected to the action of the steam. When valve m^3, m^4 is closed, the water or steam must first pass through the sieve q before being admitted to the nozzle a .

While in describing the invention reference has been made to a particular example embodying the same I wish it to be understood that my invention is not limited to the construction shown in the drawing, and that various changes may be made in the general arrangement of the apparatus and the construction of its parts without departing from the invention.

I claim:

1. A steam trap comprising a casing, a fluid inlet thereto, a fluid discharge therefrom, and means for automatically trapping the steam without employing a valve, comprising a resistance interposed in the path of the flow of the fluid and in the form of a continuously open hollow nozzle of coned form internally so as to converge in the direction of flow of the fluid, the back pressure caused by the resistance of said nozzle to the passage of liquid being greater than the normal pressure difference of the fluid between said inlet and said discharge

2. A steam trap comprising a casing, a fluid inlet thereto, a fluid discharge therefrom, and means for automatically trapping the steam and for simultaneously relieving excess pressures on their occurrence, comprising a resistance interposed in the path of flow of the fluid and in the form of a continuously open hollow nozzle of coned form internally so as to converge in the direction of flow of the fluid, the back pressure caused by the resistance of said nozzle to the passage of liquid being equal to the maximum desired pressure difference between said inlet and said discharge.

3. A steam trap comprising a casing having a fluid inlet thereto and water of condensation discharge therefrom, and means for automatically trapping the steam without employing a valve comprising a single continuously open nozzle interposed in the path of flow of the fluid and internally coned so as to converge in the direction of flow, said nozzle having its internal converging sides inclined at an angle of approximately 65 degrees, a sieve interposed in the normal path of flow in front of said nozzle and a valve located in an extension of said casing beyond said sieve, said valve being adapted when open to cause steam to pass across the face of said sieve remote

from the nozzle to remove impurities therefrom.

4. A steam trap comprising a casing having a fluid inlet thereto and water of condensation discharge therefrom, and means for automatically trapping the steam without employing a valve, comprising a single continuously open nozzle interposed in the path of flow of the fluid and internally coned so as to converge in the direction of flow, said nozzle having its internal converging sides inclined at an angle of approximately 65 degrees, a sieve interposed in the path of flow in front of said nozzle, a valve located in an extension of said casing beyond said sieve, said valve being adapted when open to cause steam to pass across the face of said sieve remote from the nozzle to remove impurities therefrom, and means for inspecting said sieve.

5. A steam trap comprising a casing having a steam inlet thereto and a discharge for water of condensation therefrom, a continuously open conical nozzle interposed in the path of the flow and converging in the direction of flow, said nozzle having its converging sides inclined at an angle of approximately 65 degrees, a sieve movably mounted in front of said nozzle to intercept impurities and means for moving said sieve so that its surface remote from the nozzle is swept over by steam current to remove impurities collected thereon.

6. A steam trap comprising a casing having a steam inlet thereto and a discharge for water of condensation therefrom, a blow off valve in said casing, a continuously open conical nozzle in said valve and converging in the direction of flow of steam and water of condensation through the steam trap and a cylindrical sieve mounted on said valve and interposed in front of the continuously open nozzle.

7. A steam trap comprising a casing having a steam inlet thereto and a discharge for water of condensation therefrom, a blow off valve rotatable in said casing, a continuously open conical nozzle mounted in said blow off valve, said nozzle converging in the direction of flow of the steam and water of condensation, a cylindrical sieve mounted to rotate with said valve and surrounding the widest end of said nozzle, said sieve being disposed so that the steam entering by the inlet to the casing passes substantially tangential thereto.

8. A steam trap comprising a casing having a steam inlet thereto, and a tubular discharge for water of condensation therefrom, a valve body in the form of a sleeve screwing on said tubular discharge, an inner flange on said valve body for normally engaging said tubular discharge and for closing the same, and a continuously open conical nozzle carried by the flange and converging in the di-

rection of flow of the fluid through the steam trap.

9. A steam trap, comprising a casing having a steam inlet thereto and a tubular discharge for water of condensation therefrom, a valve body in the form of a sleeve, screwing in said tubular discharge, an inner flange on said valve body for normally engaging said tubular discharge and for closing the same, 5 a continuously open conical nozzle converging in the direction of flow of the fluid through the steam trap and located centrally on said flange and a cylindrical sieve mounted on said flange and surrounding the wide 10 end of said nozzle.
10. A steam trap comprising a casing having a steam inlet thereto and a tubular discharge for water of condensation therefrom, a valve body in the form of a sleeve screwing 20 on said tubular discharge, an inner flange on said valve body for normally engaging said tubular discharge and for closing the same, a continuously open conical nozzle forming a resistance in the path of flow of the fluid and 25 converging in the direction of flow and located centrally on said flange, and a cylindrical sieve mounted on said flange and surrounding the wide end of said nozzle said 30 sleeve being held to rotate with said screwed sleeve.

11. A steam trap comprising a casing having a steam inlet thereto and a tubular discharge for water of condensation therefrom, a valve body in the form of a sleeve threaded on to said tubular discharge, an inner flange on said threaded sleeve for normally engaging said tubular discharge to close the same, a continuously open conical nozzle forming a resistance in the path of flow and converging in the direction of said flow, said nozzle 40 being located centrally of said flange and a cylindrical sieve carried by said flange to rotate with said threaded sleeve and surrounding the wide end of said nozzle, said sieve being located so that steam entering by the inlet sweeps tangentially over the outer cylindrical surface of the sieve. 45

12. A steam trap comprising a casing, a fluid inlet thereto, a fluid discharge therefrom, a blow-off valve in the path of the fluid from said inlet to said discharge, a continuously open and downwardly converging nozzle in the said valve and forming a resistance to the flow of fluid through said trap when said blow-off valve is closed and 50 a sieve mounted over said nozzle and rotatable with said valve. 55

In testimony whereof I hereunto affix my signature.

FREDERIK BASENAU.
